UNITED STATES PATENT OFFICE.

WILLIAM CLIFFORD, OF JEANNETTE, PENNSYLVANIA, ASSIGNOR TO ELLIOTT COMPANY, OF PITTSBURGH, PENNSYLVANIA, A CORPORATION OF PENNSYLVANIA.

MINE-VENTILATING APPARATUS.

1,107,264.

Specification of Letters Patent. Patented Aug. 18, 1914.

Application filed January 4, 1912, Serial No. 669,329. Renewed January 8, 1914. Serial No. 811,098.

To all whom it may concern:

Be it known that I, WILLIAM CLIFFORD, residing at Jeannette, in the county of Westmoreland and State of Pennsylvania, a citizen of the United States, have invented or discovered certain new and useful Improvements in Mine-Ventilating Apparatus, of which improvements the following is a specification.

10 My invention relates to apparatus used in the ventilation of mines.

The object of my invention is to provide means to prevent such apparatus from becoming inoperative when, in the case of an 15 emergency, it is used to exhaust heated gases from a mine.

In the accompanying drawings, which form part of my specification, and in which the several features of my invention are 20 illustrated, Figure 1 is a horizontal sectional view of apparatus designed for the ventilation of a mine, the plane of section being through the axis of the rotary drum which forms part thereof; Fig. 2 is a vertical sectional view taken on the line II—II, Fig. 1; Fig. 3 is a vertical sectional view taken on the line III—III, Fig. 1; Fig. 4 is a vertical sectional view on larger scale taken on the line IV—IV, Fig. 3; Fig. 5 is a plan 25 view of the bearings or pillow blocks for the axle of the rotary fan, which are shown in vertical section in Fig. 4; and Fig. 6 is a view in vertical section taken on the line VI—VI, Fig. 5, and at right angles to the 30 plane of section of Fig. 4.

In ventilating apparatus used in mines, it is the usual practice to provide means which may operate either to withdraw or 35 exhaust gas or foul air from the mine or to 40 impel fresh air into it, suitable means being employed, adjustable by the operator, to cause the apparatus to operate in either alternative manner, as may be desired. To such an end such apparatus is constructed, 45 in general respects, after the manner shown in Figs. 1 and 2, wherein a drum 1 is shown mounted upon a rotary shaft 2 and inclosed within a suitable casing 3. The said drum is preferably of the double-inlet type, and 50 the casing 3 accordingly provided with inlet-openings 4 on each side of the said drum, the said openings leading from passageways 5, which have door-controlled communication with a mine shaft 6 and with the open 55 air.

The outlet from the said casing is so arranged and controlled by a suitable gate 7, 8, that when the said gate is in the substantially vertical position indicated at 7 the impelled air will pass out the chimney 9, and when the gate is in the general horizontal position indicated at 8 the impelled air will pass through the passageway 11 and down the mine shaft 6. In such a fan construction suitable swinging doors are provided 60 at the ends of the passageway 5 for controlling the source of the air pumped by the fan. The doors 12, at the right end of the said passageway 5 are effective in their alternate full-line and dotted-line positions to throw 65 the mine shaft 6 in communication with either the fan inlet-eyes 4 or the fan outlet passageway 11, respectively; and the doors 13, at the opposite end of the passageways 5, are effective, when in closed full-line position, to direct foul air from the mine into the fan inlet eyes 4, and when in open dotted-line position to provide the inlet eyes with 70 communication from the open air.

Such a structure, as before stated, may be 75 effective to exhaust air from a mine or impel air thereto. When the outlet gate 7, 8 is in a general vertical position, as indicated at 7, and the doors 12 and 13 are in the positions shown in full lines in Fig. 1, foul air 80 will be exhausted from the mine; and the course of flow of such air will be from the shaft 6, through passageways 5, and inlets 4, into the casing 3, from which it is driven out, by means of the rotary drum, through the 85 chimney 9. By adjusting the outlet gate 7, 8 so as to be in the position indicated at 8, and by swinging the doors 12 and 13 to their dotted positions, fresh air drawn from outside may be driven by the fan, through the 90 passageway 11 and down the shaft 6.

When an explosion or a fire occurs in a mine the air and the gases of explosion are frequently of such temperature (when taken into the fan operated as described above to 100 exhaust such gases from the mine) as to render the fan inoperative; and in view of this fact my invention has to do particularly with such fans when they are operated in this manner, and is directed specifically toward providing a cooling system for all parts of the fan liable to be destroyed or rendered inoperative, when exhausting such heated gases. To such an end I preferably provide passageways or 105 110

conduits, through which a stream of cooling fluid (preferably water) may flow and be projected upon exposed parts of the fan, the conduits preferably being so disposed 5 as to provide a water sheath around the exposed and bearing portions of the shaft; and I also arrange the lubricating oil basin in such a manner as to cause the oil contained therein to be cooled by the said 10 conduits. The bearings 17 and 17^a, which rotatably support the shaft 2, preferably consist of two-part pillow blocks, having a base 18 secured to a support 19, and a cap 20 secured to the said bottom or base portion. The said base 18 is provided preferably with two sets of chambers, water chambers 21 and 21^a, and oil chambers 22 and 22^a. Suitable water passageways 23 may be provided in the cap 20 to connect the 15 water chambers 21 and 21^a, the said passageways preferably being so disposed as to surround the shaft 2 without having communication therewith. Oil passageways 24 may be provided to connect the oil chambers 22 and 22^a, the said oil passageways likewise surrounding the shaft but having communication therewith. Inlet pipes 31 may be properly attached to the base 18 so as to have communication with the chamber 21, 20 and (having particular reference to the pillow block or bearing 17) the chamber 21^a of the said base may be provided with two outlet orifices 25 and 26. To the orifice 25 a suitable nozzle 27 may be secured, the said 25 nozzle being so placed as to direct a stream of water upon the more exposed portions of the rotating drum, that is to say, upon the hub with the blades which it carries; and the orifice 26 may communicate with an annular chamber 28 surrounding the 30 shaft 2, which chamber may have at its end a pipe 29 adapted to direct a stream of water upon the shaft-supporting block 30. It will be observed of this construction that 35 water, entering through the inlet pipes 31, may flow from the chamber 21 through the passageways 23 to the chamber 21^a, from which a part of it flows through the orifice 25 and is directed upon the exposed part of 40 the fan by means of the nozzle 27; while another quantity of the water flows through the orifice 26 into the chamber 28, and from thence is directed upon the block 30 by means of the curved pipe 29. In its passage 45 through this conduit system, and in its projection upon the drum, the water is effective to keep the shaft, bearings, and drum from becoming heated to such a tempera-

ture as has heretofore rendered the fan structure inoperative. It will also be understood that the flow of the water, as described, may be controlled by hand whenever such flow is necessary, or a thermostatic valve, such as is well known in the art, may be installed in the system and so arranged as to operate at a predetermined 60 temperature.

The oil chambers 22 and 22^a which communicate with each other by the passageways 24, are preferably disposed adjacent 70 to the water chambers 21, 21^a and passageways 23, to the end that the lubricating oil may be kept cool; and the oil may find its way to the shaft 2 through suitably provided oil-ducts 32. In this construction, also, a drum 75 48 may be secured to the shaft 2 to the end that the oil may be kept in circulation while the shaft rotates, and an opening 49 may be provided for filling the oil-chambers.

I do not wish to limit myself to the details of construction shown herein, for obviously many changes may be made by those skilled in the art without departing from the spirit of my invention.

I claim herein as my invention:

1. In a mine ventilating fan, the combination with a rotary fan, a housing including an inlet passageway for the said fan, and an operating shaft for the said fan extending through the inlet passageway; of a pair of pillow-blocks affording bearings for the said shaft and provided with water chambers adjacent to the said shaft, a fluid containing chamber surrounding the said shaft within the passageway and communicating with a pillow-block water chamber, and a supply conduit leading to one of the said chambers, substantially as described.

2. In a pillow block for a mine-ventilating fan-shaft, the combination of water and oil chambers surrounding the shaft bearing portion of the said block, the said oil chamber being in communication with and affording a supply of oil to the said shaft, the said water chamber affording a cooling medium for the shaft bearing and for oil within the said oil-chamber, and a water supply conduit connected to the said water chamber, substantially as described.

In testimony whereof I have hereunto set my hand.

WILLIAM CLIFFORD.
